UNITED STATES PATENT OFFICE.

EDWARD VICTOR WETZEL AND MARGARET WETZEL, OF NEW YORK, N. Y.; SAID
EDWARD VICTOR WETZEL ASSIGNOR TO SAID MARGARET WETZEL.

PUZZLE GAME.

1,257,432.

Specification of Letters Patent. Patented Feb. 26, 1918.

Application filed October 18, 1917. Serial No. 197,200.

To all whom it may concern:

Be it known that we, EDWARD VICTOR WETZEL and MARGARET WETZEL, citizens of the United States, residing at New York, in 5 the county of New York and State of New York, have invented certain new and useful Improvements in Puzzle Games, of which the following is a specification.

The present invention relates to games 10 and has for its object to provide a puzzle game for children, consisting of a set of rods or rolls each bearing on its circumference portions of differently colored designs or pictures so arranged that when the rolls 15 or rods are placed in a certain position relative to one another the portions of one color will complement one another and compose one complete picture or design, and when the rolls or rods are in a certain different 20 position then the portions of another color will complement one another and compose another picture.

Another object of our invention is to provide a suitable container for said rolls in 25 which the latter will be held constantly in contact with one another to produce the desired effect but be allowed of being rotated around their longitudinal axes.

With these and other objects in view our 30 invention consists in the construction, combination and arrangement of parts as will be hereinafter more fully described and set forth in the appended claims.

Reference is had to the accompanying 35 drawing in which similar characters denote corresponding parts, and in which Figure 1 is a top plan view of the game showing the rods arranged in such a position that the portions of one color make up one of the designs or pictures; Fig. 2 is a similar view showing the rods in a different position in 40 which the portions of another color make up another design or picture; Fig. 3 is an enlarged section on line 3-3 of Fig. 1 and 45 Figs. 4 and 5 denote an individual rod in different positions showing portions of differently colored designs.

The game substantially consists of a set 50 of oblong members in form of rods or rolls α made of wood or other suitable material and on the circumference of which are painted or otherwise applied portions or sections a^1 , a^2 of differently colored designs or pictures of which the portions of one 55 color when the rods or rolls are placed into

a certain position relative to one another will complement one another completing the entire design or picture and of which those of another color when the rods are in a certain different position will complete another design or picture. The game is to be used in combination with well known pattern sheets or boards each containing a design or picture of a different color so that the user in order to reproduce the design by 60 the rods may follow the corresponding pattern. The portions or sections a^1 , a^2 of the designs on the circumference of each rod are reproductions of parallel sections of the patterns.

In order to obtain the desired effect, the rods or rolls must be held constantly in close contact with one another and to this end we provide a container b the bottom b^1 of which is provided with a number of flutes or corrugations one for each rod or roll. These flutes or corrugations prevent the displacement of the rods relative to one another, but permit the rotation thereof around their axes. c denotes a transparent cover which 70 may be used for the box.

The differently colored portions or sections of the designs on the rods may be arranged on different sides thereof so that a mere turning of the rods around their axes 75 from one position to another may change the character of the design or in order to render the solution of the puzzle more laborious the differently colored sections on the rods may be so placed as to require not only 80 the turning of the rods but also the change of the order in which the rods have been 85 previously arranged in the box.

What we claim and desire for Letters Patent is:

1. A puzzle game consisting of a set of 95 independent and disconnected rods capable of being rotated around separate axes and each bearing on its circumference portions or sections of differently colored designs or pictures, of which those of one color when the said rods are rotated around their axes and brought to lie in a certain position will complement one another to complete one of the designs or pictures and those of a different color when the rods are in a different position will complement one another to present another design or picture.

2. A puzzle game comprising a set of 100 independent and disconnected rolls capable 105

of being rotated around separate axes and each having on its circumference portions or sections of differently colored designs or pictures, of which those of one color when 5 the rolls are rotated around their axes and brought to lie in one position complement one another producing one design and those of the other color when the rolls are turned into another position produce another 10 sign.

3. A puzzle game comprising a set of independent and disconnected rolls capable of being rotated around separate axes and each bearing on its circumference portions 15 of differently colored designs, which portions are arranged on different sides of the circumference and of which those of one color when the rods are rotated around their axes and brought to lie in one position produce one design and those of another color 20 when the rods are in a different position produce a different design.

4. A puzzle game comprising a set of rolls having on their circumference portions or 25 sections of differently colored designs, of which those of one color when properly placed are adapted to complete one design

and those of the other are adapted to complete another design and a container having a fluted or corrugated bottom, with one flute 30 or corrugation for each roll, whereby the rolls are held constantly in contact with one another.

5. A puzzle game comprising a set of disconnected rolls adapted to be arranged in a 35 horizontal plane alongside each other and with their axes parallel to one another, and to be capable of being rotated each around its individual axis, each roll bearing on its circumference portions of differently colored 40 designs arranged on different sides of the circumference, and of which those of one color when the rolls are in one position produce one design and those of another color 45 when the rolls are in a different position produce a different design.

In testimony whereof we affix our signatures in presence of two witnesses.

EDWARD VICTOR WETZEL.
MARGARET WETZEL.

Witnesses:

AUGUST GRAF,
CHARLOTTE BEHUSEN.
